UNITED STATES PATENT OFFICE.

FRED E. LEE, OF DOWAGIAC, MICHIGAN.

DESIGN FOR A STOVE OR RANGE.

SPECIFICATION forming part of Design No. 26,657, dated February 16, 1897.

Application filed March 9, 1896. Serial No. 582,490. Term of patent 14 years.

To all whom it may concern:

Be it known that I, FRED E. LEE, a citizen of the United States, residing at the city of Dowagiac, in the county of Cass and State of Michigan, have invented a certain new and useful Design for a Cooking Stove or Range, of which the following is a specification.

My invention relates to a design for a cooking stove or range.

My invention relates more particularly to the stove or range illustrated in the accompanying drawing, which presents a perspective view of the stove or range constructed in accordance with my design.

The leading feature of my design is more particularly the peculiar configuration and ornamentation of the various portions of the stove.

The outline features of the design are not essentially new.

The stove shown is supported upon a base B, provided with legs which are ornamented as shown in the accompanying drawing, each leg being so formed as to present a convenient name-plate for the name of the stove. Detachably supported upon this base is the main body of the stove A, the various parts of which are ornamented, substantially as indicated in the drawing. The name-plate of the door is preferably finished in nickel and polished to increase the effectiveness of the design. The reservoir C is supported to the

back of the stove and is ornamented, as illustrated. The ornamental bracket D extends up on the side of the stove which is ordinarily placed next to the wall and is ornamented, as indicated, and supports a shelf E at the top, as shown in the drawing. These parts enumerated form a complete cooking stove or range very ornamental in its character, and it will be readily understood that each part here shown, while it enters into the entire design, is capable of use with other designs of cooking-stoves and also that the bracket D, with its shelf E, can be placed upon other styles of cooking-stoves and present a very ornamental appearance.

Having thus described my invention, what I claim as new, and desire to secure by Letters Patent, is—

1. The design for a cooking stove or range substantially as described and shown.
2. In a design for a cooking stove or range, the base B, substantially as described and shown.
3. In a design for a cooking stove or range the ornamental shelf-bracket D, substantially as described and shown.

In witness whereof I have hereunto set my hand and seal in the presence of two witnesses. 60

FRED E. LEE. [L. S.]
